UNITED STATES PATENT OFFICE.

RUDOLPH HERMAN, OF CLEVELAND, OHIO.

DESIGN FOR A BILLIARD-TABLE.

SPECIFICATION forming part of Design No. 13,440, dated November 21, 1882.

Application filed October 16, 1882. Term of patent 14 years.

To all whom it may concern:

Be it known that I, RUDOLPH HERMAN, a citizen of the United States, residing at Cleveland, in the county of Cuyahoga and State of Ohio, have invented a new and original Design for Billiard-Tables, of which the following is a specification, reference being had to the accompanying drawings, forming part thereof.

10 Figure 1 is a perspective view of my newly-designed billiard-table. Fig. 2 is a detached view of ornament on end panel of the table.

15 My design consists in the ornamentation of the table by raised carved or molded stems and leaves representing oak, and are arranged upon the panels, side and end rails, and the legs of the table, substantially as shown.

20 The side panels, A, have represented upon them branches and leaves, the butt-ends of the branches crossed at the middle, with the leaves pointing to the right and left. Beneath this a depending ornamental carved piece, B, is attached, consisting of an oak branch and

leaves on a mottled ground-work. The end of the table is ornamented with a circular carved 25 panel-piece, C. At the four corners of the table are attached strips D D. These also are ornamented on the surface with carving of leaves. The lower edge of the side and end rails are ornamented with a running vine of 30 small leaves. The legs E also are ornamented on their upper portion with similar carving of leaves. This ornamentation may be produced by wood carving or by plastic molding, substantially of the style represented. 35

Having described my invention, I claim—

The design for a billiard-table herein shown and described, consisting of the raised carved or molded stem-and-leaf ornamentation upon the side and end panels, rails, and legs of the 40 table.

RUDOLPH HERMAN.
